UNITED STATES PATENT OFFICE.

LAWRENCE E. BARRINGER AND GILBERT WRIGHT, OF SCHENECTADY, NEW YORK,
ASSIGNORS TO GENERAL ELECTRIC COMPANY, A CORPORATION OF NEW YORK.

INCLOSED-FUSE INDICATOR.

1,014,741.

Specification of Letters Patent. Patented Jan. 16, 1912.

Application filed July 9, 1909. Serial No. 506,739.

To all whom it may concern:

Be it known that we, LAWRENCE E. BARRINGER and GILBERT WRIGHT, citizens of the United States, residing at Schenectady, 5 county of Schenectady, State of New York, have invented certain new and useful Improvements in Inclosed-Fuse Indicators, of which the following is a specification.

The present invention relates to thermal 10 cut-outs, and more especially to the indicating means for inclosed fuses whereby the condition of the main element of the fuse is made visually apparent on the outer surface of the casing.

15 The object of our invention is to provide an indicator of this character which will positively perform its function and produce a clearer and more distinct indication than devices of this character heretofore in use.

20 In the accompanying drawing, Figure 1 shows in part side elevation and part section an ordinary inclosed fuse with our indicator attached thereto; Fig. 2 is a magnified section of the indicator and adjacent portion 25 of the fuse casing; Fig. 3 is a plan view of the indicator before operation; and Fig. 4 is the same after operation.

The fuse shown in the drawing consists 30 of a casing having a central tube 1 of fiber with its ends inclosed by metallic caps 2 through which extend the contact blades 3, to the inner ends of which the main fuse element 4 is connected. An auxiliary fuse element 5 extends along the inner surface of 35 the casing connecting the end contacts 3 in multiple with the main element 4, and the middle portion of the auxiliary element 5 is threaded through small apertures 6 in the wall of the fiber tube 1 and across a recess 40 or chamber 7 formed in the outer surface of the tube.

Over the portion of the auxiliary element 5 exposed on the outer surface of the fiber tube is disposed our improved indicator 8 45 which is held in place by a label 9 of paper pasted thereover and provided with a center aperture 10 through which the indicator 8 is normally seen, as shown in Fig. 3.

The indicator consists of fibrous material, 50 such as rice paper, which has been treated

with a solution of some oxidizable salt such as potassium chlorate 11 to facilitate ignition under the action of the heat evolved upon disruption of the auxiliary element 5 and insure complete combustion of the fiber. 55 This solution may be applied by dipping the fibrous material in a bath thereof or the solution may be sprayed or poured thereon.

In order to hold the potassium chlorate, 60 or other oxidizing salt in permanent contact with the fibrous sheet, to prevent absorption of moisture and to facilitate the combustion thereof, we apply a flexible non-hygrosopic coating 12, such as collodion, to the treated fibrous material. This coating 12 may be 65 applied either by dipping or spraying or pouring over the fibrous material a solution of collodion.

In order to render visually apparent 70 whether or not the coating material has been properly applied to all parts of the fibrous material we discolor the coating material by means of a die soluble therein such as malachite green.

The object of providing the recess or 75 chamber 7 in the fiber tube beneath the auxiliary element 5 is to afford a supply of air to the inner surface of the indicator as well as to the outer surface and at the same time prevent conduction of heat from the external portion of the auxiliary element. 80

We do not desire to restrict ourselves to the particular constituents or arrangement 85 of parts herein described and shown, since it is apparent that they may be changed without departing from our invention.

What we claim as new and desire to secure by Letters Patent of the United States, is,—

1. A fuse indicator comprising fibrous 90 material coated with a readily combustible and non-hygrosopic material.

2. A combustible indicator comprising a sheet of fibrous material coated with collodion. 95

3. A combustible indicator comprising a sheet of fibrous material chemically treated and coated with collodion.

4. A combustible indicator comprising a sheet of fibrous material treated in oxidiz- 100

ing salt and then coated with a readily combustible and non-hygroscopic material.

5. A combustible indicator comprising a sheet of fibrous material treated in oxidizing salt and then coated with collodion.

6. An inclosed fuse having an air chamber formed in the outer wall, an auxiliary fuse member crossing said air chamber, and a combustible indicator disposed in contact

with said auxiliary fuse and extending over 10 said air chamber.

In witness whereof, we have hereunto set our hands this 7th day of July, 1909.

LAWRENCE E. BARRINGER.
GILBERT WRIGHT.
